(57) **CLAIM**

The ornamental design for a strut suspension spacer combination, as shown and described.

DESCRIPTION

FIG. 1 is a front top perspective view of the strut suspension spacer combination of the present invention;
FIG. 2 is a rear, bottom perspective view of the spacer combination shown in FIG. 1;

FIG. 3 is a front view of the spacer combination shown in FIG. 1;

FIG. 4 is a back view of the spacer combination shown in FIG. 1;

FIG. 5 is a left end view of the spacer combination shown in FIG. 1; and,

FIG. 6 is a right end view of the spacer combination shown in FIG. 1.

The broken lines showing voids and contours are for illustrative purposes only, and forms no part of the claimed design.

1 Claim, 5 Drawing Sheets
